BOTTLE CAP

Vincent Guarnaschelli, Corona, N. Y.

Application July 25, 1944, Serial No. 546,464

1 Claim. (Cl. 215—38)

1

This invention relates to bottle caps, and aims to provide a novel removable and replaceable cap so constructed that it may be slid on to provide a bottle seal and slid off to obtain access to the contents.

Another object of the invention is the provision of releasable and yieldable locking means forming part of the cap, whereby the cap is releasably locked in sealing position on the bottle.

The above and other objects will become apparent in the description below, wherein characters of reference refer to like-numbered parts in the accompanying drawings. It is to be noted that the drawings are intended to serve the purpose of illustration only, and it is neither desired nor intended to limit the invention necessarily to the specific details of construction shown except insofar as they may be deemed essential to the invention.

Referring briefly to the drawings,

Fig. 1 is a bottom perspective view of the cap with a washer mounted therein.

Fig. 2 is a bottom plan view of the cap.

Fig. 3 is a front view of the cap when stood on one side.

Fig. 4 is a cross-sectional view taken on the line 4—4 of Fig. 2.

Fig. 5 is a view similar to Fig. 4 but showing the cap applied to a bottle with a washer mounted thereunder.

Fig. 6 is a side elevational view of a modified form of the cap applied to a bottle.

Fig. 7 is a longitudinal cross-sectional view of the modified form of the cap, applied to a bottle.

Referring in detail to the drawings, the numeral 10 indicates the cap as a whole, which is formed out of a unitary sheet or piece of metal, plastic, rubber, or any other composition or material. The cap 10 comprises a roof 11 having a concentric depression dished out at 12 to form on the underside of the roof an annular flat groove 13 adapted to have a washer 14 seated therein.

The roof 11 of the cap has an apron 15 depending from a portion of the periphery thereof, that is, a portion in excess of one-half of the periphery, thereby leaving an opening or mouth 16 at what will be termed the front end of the cap. The apron 15 is circular in conformation. A lip 17 is formed along the lower edge of the apron 15, as by bending the same inward, and the internal periphery 18 of this lip is semicircular intermediate the extremities thereof but the latter have their mutually opposed edges 19 mutually parallel and spaced from each other at a distance equal to the diameter of the semi-circular peripheral

2

edge 18 of the lip 17. Thus, excepting for the open end or mouth 16, the grooved portion of the roof 11, the apron 15, and the lip 17, form or enclose a semi-annular recess 20 having at each end thereof a straight extension recess 21. The washer 14, when set into its groove 13, occupies the upper portion of the recess 20—21. It is apparent that the cap may be readily slid on to a bottle 22 by moving it in the direction of the arrow, Fig. 5, after applying the mouth 16 of the cap to the top of the bottle, in an obvious manner. The cap may of course be made to use without a washer or planchet, without altering the invention in any manner. The distance between the lip edges 19 of the straight front extensions of the recess 20—21 obviously is substantially the same as the diameter of the bottle groove 23, whence the cap may be thus slid into the position shown in Fig. 5 without obstruction.

20 Provision is made as follows to provide a tight yet releasable or yieldable securement of the cap in the mounted position shown in Fig. 5. At three peripherally spaced positions, substantially as shown in Fig. 1 and Fig. 2, an upwardly curved indentation 24 or 25 is formed in both the lip 17 and the apron 15, as by punching or stamping, thereby providing somewhat yieldable projections which project into the recess 20 at the lower edge thereof. Thus, as the cap is being slid into the position shown in Fig. 5, these projections obviously yieldably engage the lower edge of the collar 26 of the bottle. The intermediate projection 25, which is positioned at the rear of the cap opposite the mouth 16, might be omitted without affecting the pressure of the mounted cap on the bottle; but it serves as a yieldable aid to the removal of the cap by pressing the front end thereof and urging it in a direction opposite that of the arrow, Fig. 5. It is to be noted that the forward end of the roof of the cap, shown at 21, above the mouth 16, is turned down along its edge to provide a reduced flange which grips the forward end of the washer and aids in applying downward pressure on the mounted cap.

45 The modified form of the cap 28 shown in Figs. 6 and 7 is substantially similar to the cap 10, excepting that its lip 17a lacks the indentations 24 and 25. Instead, this form is provided with three similarly spaced inwardly projecting punched or stamped bosses 29 the lateral two of which taper rearwardly and act in wedge-like fashion against the lower edge of the bottle collar 26 during slideable insertion of the cap in the manner above described. The intermediate or rear boss 28 serves 55 in the same fashion as the intermediate or rear

3

projection 25. In addition, the cap 28 is provided with opposed vertical punched-in recesses 30 which serve as finger grips for removal of the cap.

It is apparent from the above that a slidable bottle cap or seal has been provided which may very easily be applied to or removed from the bottle, and which will serve to provide just as tight a seal upon reapplying it after first opening the bottle as the original seal, since the cap is in no way damaged or altered by the act of removal. The straight or tangential extremities of the lip 17, which are mutually parallel and spaced apart a distance equal to the diameter of the bottle groove 23, permit of this slidable movement, 15 which would be impossible if the said extremities were merely concentric continuations of the semi-circular lip periphery 18.

Obviously, modifications in form and structure may be made without departing from the spirit 20 and scope of the invention.

I claim:

A bottle cap for a bottle having an annular bead at its mouth, comprising a substantially disc-like member adapted to cover the mouth of the bottle, said member having a depending peripheral flange extending from the peripheral edge thereof, said flange having a cut-out at the front of the cap of

5 a size which is adapted to receive said bead, said flange having circumferentially spaced inwardly extending and somewhat elongated projections in the sides thereof, said projections lying in a common plane parallel with the plane of said peripheral edge of said member, said projections tapering in a forward direction, said flange having an additional inwardly extending projection in the rear thereof lying in the said common plane, said 10 projections being adapted to engage the underside of said bead to clamp said cap on said mouth, said flange having inwardly extending indentations in the sides thereof thereby providing finger grip recesses for said cap.

VINCENT GUARNASCHELLI.
